UNITED STATES PATENT OFFICE.

ERNEST F. GREER, OF IDABEL, OKLAHOMA.

SKELETON CROWN AND FACING THEREFOR.

1,096,712.

Specification of Letters Patent. Patented May 12, 1914.

Application filed July 7, 1913. Serial No. 777,761.

To all whom it may concern:

Be it known that I, ERNEST F. GREER, a citizen of the United States, residing at Idabel, in the county of McCurtain and State of Oklahoma, have invented certain new and useful Improvements in Skeleton Crowns and Facings Therefor; and I do declare the following to be a full, clear, and exact description of the invention, such as will enable others skilled in the art to which it appertains to make and use the same.

This invention relates to improvements in skeleton artificial tooth crowns and facings therefor.

The object of the invention is to provide a skeleton crown which is simple and cheap, requiring only a very small quantity of gold to complete the crown, which avoids any gold being exposed at or near the gum margin, which is practically impossible to break by internal force, and which saves a great deal of time in the application thereof.

With these and other objects in view the invention consists of certain novel features of construction, and the combination and arrangement of parts as will be more fully described and claimed.

In the accompanying drawings: Figure 1 represents a perspective view of the crown in the condition in which it will be placed on the market; Fig. 2 is a similar view of the facing used in connection with this improved skeleton crown; Fig. 3 is a side elevation of the crown after it has been finished by a dentist, with the exception of cementing the facing thereto; Fig. 4 is a longitudinal vertical section of the completed tooth; Fig. 5 is a side elevation partly in section of a slightly different form of the invention.

In the embodiment illustrated a metallic post or pin 1 is shown of suitable size, shape and form to enter and approximately fit a prepared socket or canal in a natural tooth root. A metallic backing 2 extends longitudinally from the larger end of the pin 1 and a shoulder 3 extends laterally from the inner end of said backing at its junction with the post at the front of said backing and is varied in length according to the

length of the crown in order to cause the facing securing pin to enter the porcelain facing at the desired point. A similar shoulder 4 extends laterally from the back of the backing at its juncture with the post, said shoulder being preferably semi-circular in shape and which will be about the same

length in all cases. A facing securing pin 5 extends at an oblique angle from the front of the backing 2 adjacent the shoulder 3, said pin being inclined downwardly and adapted to enter a suitable socket in the facing to be described. The shoulders 3 and 4 unite and form a continuous abutment at the base of the pin 1 and in the inner face of said abutment is arranged a recess 6 designed to form a rim 6^a and facilitate the formation of a joint with the natural tooth root with a minimum of grinding. The backing 2 is made longer than the facing to which it is to be applied and the free edge 7 thereof is made thin and is designed to be burnished over the cutting edge of the facing to provide a protection for said cutting edge and also to assist in holding the facing firmly in operative position.

This metallic skeleton crown may be composed of ankrite or any other suitable substitute for platinum, or a portion of the metal may be composed of ankrite or any other suitable platinum substitute and gold may be added where more desirable.

A facing 8 of porcelain is shown for use in connection with this improved skeleton crown and is provided on its rear face near its inner end with an offset 9 which is designed to engage the shoulder 3 of the crown and thereby relieve the fastening pin 5 from more or less strain. Adjacent the offset portion of the facing 8 is an obliquely disposed socket 10 positioned to receive the pin 5 when the parts are assembled. This facing 8 is designed to be cemented to the outer face of the backing 2 which renders them sanitary. If desired, the facings may be made interchangeable and a dentist can thus afford to keep a well assorted stock of these crowns on hand as they are adapted to take the place of full gold crowns, full porcelain crowns, post and plate, cast crowns and anchorage crowns in bridge work or they may be converted into Richmond crowns or used as when necessary these crowns may be easily converted into facings with backings, by cutting off the post and inside shoulder.

In the use of this improved tooth the metallic and porcelain parts can be put together and ground to fit the root of the tooth in the same manner that an all porcelain crown is fitted. Very little grinding will be necessary on the metal shoulder as it is manufactured thick enough only to

allow for grinding a joint and the facing is made full long at the gum margin to adapt it to be properly fitted.

A closer fitting joint can be made with this kind of crown than with an all porcelain crown because of the fact that the facing may be removed from time to time to enable the dentist to see under the gum margin and thus grind the metallic shoulder and root of the tooth to a perfect joint. After the tooth has been fitted the thin metal edge of the backing 2 is burnished over the cutting edge of the porcelain facing and the facing is then removed. The backing is then invested without having to assemble the different parts and after investing, gold solder is flowed on the rear face of the backing and extends from the gum line on the metal shoulder to the top of the cutting edge which has been burnished over the edge of the facing. The gold surface is then polished and the facing is cemented in position and the crown is complete ready for use as shown in Fig. 3. The removal of the porcelain facing before flowing gold over the metallic surface prevents checking of the facing by the heat.

The pin 5 penetrates the facing at the thickest portion thereof at or near the longitudinal center thereof and at such an angle that the facing is not materially weakened and this peculiar positioning of the pin

serves to hold the facing in position with the crown and root on the same principle that one post holds the Davis crown in the root of a tooth and the facing is wedged in from all sides except the front.

In Fig. 5 the post 1^a is united with the front shoulder 3^a in advance of the backing 5^a and said shoulder 3^a is shown longer than shoulder 4^a to adapt it for a long tooth.

When these facings are assembled together in a bridge and it is desired to remove them before investing the bridge, it is only necessary to heat one end of a stick of wax and stick to the front surface of the facing and lift it off whereby the bridge is not distorted.

I claim as my invention:

A crown tooth comprising a metal post and backing having a laterally extending shoulder, a facing engaging pin extending obliquely outward from said backing, and a facing having an offset at one end on one face thereof for engagement with said shoulder, and a socket for the reception of said pin.

In testimony whereof I have hereunto set my hand in presence of two subscribing witnesses.

ERNEST F. GREER.
